(57) **CLAIM**

The ornamental design for an accessory for drinking cup, as shown and described.

DESCRIPTION

FIG. 1 is a top perspective view of an accessory for drinking cup showing my new design;

FIG. 2 is a bottom perspective view of the accessory for drinking cup showing my new design;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1; and,

FIG. 8 is a bottom view of FIG. 1.

Any shading and cross-hatching are not features of the design but are utilized to illustrate the surface contours of the accessory for drinking cup design in the drawings. The broken lines show portions of the accessory for drinking cup that form no part of the claimed design.

1 Claim, 8 Drawing Sheets
